UNITED STATES PATENT OFFICE.

CHARLES D'ADHÉMAR DE LABAUME, OF BORDEAUX, FRANCE.

TOILET-CABINET.

1,263,384.

Specification of Letters Patent. Patented Apr. 23, 1918.

Application filed June 29, 1917. Serial No. 177,777.

To all whom it may concern:

Be it known that I, CHARLES D'ADHÉMAR DE LABAUME, residing at Bordeaux, France, have invented a new and useful Improved 5 Toilet-Cabinet, of which the following is a specification.

This invention relates to an improved combination toilet cabinet more especially adapted for use in positions where space has 10 to be reduced to a minimum such as on board ship, in hotels, trains, corridors and similar places.

Toilet cabinets such as are usually employed for the purpose are either incomplete 15 or defective in operation and the object of the present invention is a cabinet which will give a maximum of utensils in a minimum of space.

The invention will be described with reference to the accompanying drawings.

Figure 1, is a front elevation of a complete cabinet.

Fig. 2, vertical section on line A—B Fig. 1.

Fig. 3, detail views of a seat pivoted or 25 hinged to the cabinet.

Fig. 4, vertical section of a modified construction of cabinet.

Fig. 5, front view of the lower part of the cabinet, shown in Fig. 4.

30 Fig. 6, plan and elevation of a waste or funnel with double outlets.

Fig. 7, plan and elevation of wash-hand basin.

Fig. 8, sectional elevation of a urinal 35 which can be applied to the lower part of the cabinet.

The cabinet is constructed in the usual shape and can be ornamented in any way desired by the maker. A bracket *a* for gas or 40 electricity, is affixed to the upper part of the cabinet for lighting it. Below this bracket a shelf *b* is arranged for books or trinkets. Below the shelf *b* is a cupboard *c* for holding different articles such as water bottles, 45 glasses, and the like and serving also to contain an electrical heating apparatus for heating the water supplied to the wash-hand basin. The panel closing the cupboard is made in a single piece and is provided on 50 its outer face with a mirror. It is covered by two smaller doors *d* hinged to the sides of the cabinet; the inner faces of the doors *d* are also provided with mirrors, so that when 55 open they form with the panel closing the cupboard a three sided mirror which is arranged to be inclined at will on its horizontal

axis as shown in dotted lines in Fig. 2 to allow access to be had to the cupboard *c* or for any other purpose.

A drawer *e* is arranged below the cupboard *c* to receive brushes, combs, and other toilet articles.

The upper part of the cabinet described above is carried on a lower part of greater depth to which is pivoted at a convenient 65 height a bracket *f* carrying a wash-hand bowl *g* of the shape shown in Fig. 7. The wash-hand bowl *g* is located in the cabinet when the bracket *f* is closed. The bracket *f* is provided on its outer face with a mirror *h* which can 70 be covered by a panel *i* pivoted to the bracket *f*. When the bracket *f* is in its closed position the panel *i* may assume a horizontal position to form a writing or toilet table, the mirror *h* being used by the person using 75 the cabinet.

When the bracket *f* is closed the wash-hand bowl is automatically emptied into the waste funnel fixed in the interior of the cabinet and having on its upper edge a rubber 80 pad *j* to receive the side of the bowl and form a tight joint.

To provide for the rolling movement on board a ship the funnel *J* may be provided with two waste outlets *w* so that when the 85 funnel is full of water and the ship slopes to larboard the water escapes through one of the outlets and when it slopes to starboard it escapes through the other outlet so that the water will not remain stagnant in the 90 bowl; moreover the rubber packing *j* causes the water to pass completely into the funnel *J* even during rough weather instead of being spilled over the cabinet.

The water supply tap *k*, soap tray *l* and 95 other usual accessories are arranged over the bowl *g*.

An opening is formed in the front panel of the cabinet below the bowl *g* to receive an articulated seat *m* of the form shown in 100 Figs. 1, 2 and 3. This seat can be pulled into position by the hand and be used as a seat during toilet or for writing at the table formed by the panel *i*.

The seat *m* is carried on a bar 1 pivoted 105 at one end to a rod 2 and at the other to a support 3. The rod is pivoted on a stud 4 affixed to the lower part of the cabinet so that when a pull is exerted on the seat to bring it out of the cabinet the rod 2 takes 110 up an inclined position as shown in Fig. 3 and the support 3 a vertical position to sup-

port the seat. To give more stability to the seat the support 3 is made wider at the base and carried on two arms 5 which will slide easily over the floor. The exact positions of the parts are determined by the person sitting on the seat to give a convenient height for using the table.

The spaces in the lower part of the cabinet at each side of the seat are used to form 10 two small cupboards with doors in one of which a chamber utensil *n* and in the other a spittoon *o* or other article can be placed as desired. On the sides of the cabinet different devices can be arranged such as a 15 coat hook *p*, a towel rail, a pipe stand *r*, an umbrella stand or the like. It can also be provided with an extensible stand *q* to carry a glass and bring it in a position near to a person lying down.

20 The cabinet above described is particularly applicable for use on board ship where it must take up as small a space as possible. On land in hotels for example where more space can be utilized the modification shown 25 in Figs. 5 and 6 can be employed.

In this construction the cupboard *c* holds 30 a gas or electric radiator *s* which permits either hot or cold water to be used as desired. The seat is replaced by a foot bath *t* pivoted on a slide *u* so that it can be turned into the position in the cabinet shown in dotted lines in Fig. 4. A waste funnel *v* receives the water from the bath *t* and taps *x* supply hot and cold water thereto.

35 For use in an office the foot bath can be replaced by a towel rail or by a urinal as

shown in Fig. 8, the bowl 6 of which can swivel in the waste pipe 7 on which it is mounted. The urinal is turned to bring it out of the cabinet and is turned in the opposite direction to return it thereto.

The operation of all the parts described is very simple and the combination of the parts give a maximum of uses with a minimum of space.

45 Having now particularly described and ascertained the nature of my said invention and in what manner the same is to be performed, I declare that what I claim is:

In a toilet cabinet of the character described, the combination of a number of superimposed compartments for receiving various articles of personal use when making toilet, a pivoted bracket, a wash basin carried by said bracket, a waste funnel into 50 which said basin is emptied upon the swinging of said bracket around its pivot, a rubber packing on said funnel for cushioning and tightening the joint between basin and funnel, and a mirror arranged on the under 55 side of the bracket carrying the wash-hand basin and a panel pivoted to the bracket to form a table when the bracket is closed and the mirror uncovered substantially as described.

60 65 In testimony whereof I affix my signature in presence of two witnesses.

CH. D'ADHÉMAR DE LABAUME.
